UNITED STATES PATENT OFFICE

2,610,415

MARINE PLOW

Donald Morris Glaser, Lafayette, La.

Application February 2, 1949, Serial No. 74,078

2 Claims. (CL. 37—54)

1

This invention relates to a plow of novel construction for the primary purpose of digging trenches or ditches of predetermined depth in the bed of a body of water, particularly a river, or shallow stream; for the subsequent laying of submarine cables, sewer pipes, oil or pipe lines, etc.

An important object of this invention is to provide a plow of novel construction which is detachably secured to a floatation tank which may be filled with fluid such as water when it is desired to lower the plow to the bottom of the water for the purpose of opening a trench. Conversely, the tank may be emptied to bring the plow back to the surface of the water.

A still further object of this invention is to provide a plow of the character described in which the floatation tank is further provided with separate compartments for selectively receiving water to ballast the floatation tank to a desired degree and to enable the operator to add or eliminate water when desired. The floatation tank, when filled with water, drags on the surface of the water bottom and provides the means of having the trench dug at an even depth.

A still further object of this invention is to provide a marine plow of the character described including a jet tube positioned immediately in front of the plow itself for the delivery of a spray of water to the bed for softening the latter while a trench is being dug by the plow.

A still further object of this invention is to provide a plow of the character described in which the plow itself is especially constructed and designed to dig a trench and remove the dirt therefrom while simultaneously preventing the re-filling of the trench with dirt removed.

These, together with various ancillary objects and features of the invention which will later become apparent as the following description proceeds, are attained by the device, a preferred embodiment of which has been illustrated by way of example only in the accompanying drawings, wherein:

Figure 1 is a side elevational view of the plow of the instant invention as attached to a boat;

Figure 2 is a side elevational view of the plow shown detached from the boat;

Figure 3 is a top plan view of the plow;

Figure 4 is an end elevational view looking to the left on Figure 2;

Figure 5 is a sectional view taken substantially in the plane of section line 5—5 of Figure 3;

Figure 6 is a side elevational view of the plow itself shown detached from the floatation chamber; and

2

Figure 7 is a fragmentary diagrammatic view illustrating the means of delivering water to the jet.

Specific reference will now be made to the drawings. In the several views in the accompanying drawings and in the following specification like reference characters indicate corresponding elements throughout.

The device of the instant invention consists essentially of two important structural features, namely, a floatation chamber generally indicated at 10 and a plow removably attached thereto generally indicated at 12. As shown clearly in Figures 2, 3 and 5, the floatation chamber 10 is a hollow housing in the shape of an arrowhead having top and bottom walls 14 and 16, rearwardly diverging side walls 18 and 20 and inwardly converging rear walls 22 and 24. The front or apex of the floatation chamber is provided with an apertured plate 26 for adjustably receiving a hook 28 attached to a cable 30 operated by a winch 32 on the pulling vessel 34.

The floatation chamber is further provided with inwardly disposed vertically extending partitions or baffles 36, see Figure 3, preferably arranged in the form of a triangle so that four separate and distinct compartments 38, 40, 42, and 44 are provided. Each of the compartments includes a pair of vertically extending pipes or conduits 46 and 48 which extend through the top wall 14 of the housing 10 and carry suitable couples 50 and 52, respectively. One of the pipes 46 preferably extends to a position adjacent the bottom 16 of the housing 10 and will be employed for selectively introducing a fluid such as water into the compartment while the other conduit 48 extends into the compartment just beyond the top wall 14 and is adapted to be secured to a compressed air line for blowing out the water from the conduit 46 (when opened) when it is desired to remove water from the compartment. Thus it will be seen that a floatation chamber is provided which can be readily and easily filled with water to supply ballast for the attached plow 12. By providing separate compartments and means for selectively filling each of the compartments with water and means for removing the water from each of the compartments, the weight of the ballast can be desirably and adjustably shifted depending upon the depth of trench desired.

At this point, the exact construction of the plow 12 will be described. A particular construction is provided so that a proper trench can be formed at the water bed or bottom 54 in such a manner that the dirt removed from the trench will be prevented from re-entering the trench.

The plow consists of a central vertically extending member 56 which is cut out at its forward end as at 58 to provide a recess for retaining a transversely extending plate 60 across the top edge of the plow. To the rear of the floatation chamber 10 and suitably supported upon the bottom wall 16 thereof is a further plate or block 62 and bolts 64 are provided which extend through the plate 60 and the block 62 for securing the central member and other associated plow elements to the floatation chamber. 10

Intermediate the ends of the central member 56 and adjacent the top edge thereof, a pair of rearwardly diverging dirt-spreading wings or arms 66 are provided which are welded or riveted to the central member 56 as at 68. The rear or free edges of the wings are preferably interconnected by means of a transversely extending rear plate 70. Secured to the dirt-spreading wings 66 are a pair of arms 72, preferably in the form of angles which are apertured at their free ends and inturned as at 74 to receive a bolt 76 for attachment to the rear walls 22 and 24 of the floatation chamber 10. Welded or riveted to the bottom edges of the wings 66 and further secured to the front corners of the central plate 56 are arcuated mold boards 78. This construction of a plow permits the effective digging of a trench, removal of dirt therefrom, and prevention of re-entry of the dirt within the trench. 15

To soften the river or stream bottom 54 just in front of the plow, a jet tube 80 is provided which passes through the top and bottom walls of the floatation chamber 10 and terminates just in front of the front edge of the central plate 56 of the plow. The jet tube 80 is threaded as at 82 to receive an appropriate coupling attached to a water delivery line 84 operatively connected to a pump 86 carried on the vessel 34, which pump is appropriately driven by a motor (not shown). The pump draws water from the river or stream via a valved conduit 88 which extends into the water and which has a screen 90 attached thereto to filter the water before it is delivered to the jet 80. 20

Thus it will be seen that an extremely effective plow is provided that can be readily pulled by a vessel. The plow is of such construction that a trench of appropriate depth is dug and the plow may be easily raised and lowered by merely withdrawing or adding water to selected compartments in a floatation chamber attached to the plow. 25

In view of the foregoing description taken in conjunction with the accompanying drawings it is believed that a clear understanding of the de- 30

vice will be quite apparent to those skilled in this art. A more detailed description is accordingly deemed unnecessary. 4

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. In a marine plow an arrowhead-shaped floatation chamber comprising top and bottom walls, rearwardly diverging side walls, said side walls terminating in an apex, a forwardly extending apertured plate secured to the apex of said side walls, forwardly extending, inwardly converging rear walls secured to the rear ends of said side walls, a plurality of baffles dividing said chamber into a plurality of compartments, a plow, a plate mounted on said plow, a plate mounted on said chamber, means joining said plates together for mounting said plow on said chamber, means operatively associated with said compartments for selectively filling and removing liquid from said compartments. 20

2. In a marine plow an arrowhead-shaped floatation chamber comprising top and bottom walls, rearwardly diverging side walls, said side walls terminating in an apex, a forwardly extending apertured plate secured to the apex of said side walls, three baffles arranged in triangular formation in said chamber, said baffles dividing said chamber into four separate compartments, a plow, a plate mounted on said plow, a plate mounted on said chamber, means joining said plates together for mounting said plow on said chamber, means operatively associated with said compartments for selectively filling and removing liquid from said compartments. 30
